UNITED STATES PATENT OFFICE.

JOSEPH A. SHEPHERD AND WILLIAM L. JOHNSTON, OF DETROIT, MICHIGAN.

SIGNAL EXHIBITOR.

Application filed January 16, 1922. Serial No. 529,550.

This invention relates to a signal exhibitor, and has special reference to that class of exhibitors which are illuminated and adapted for displaying a plurality of signs to indicate direction of travel and conditions incident to traffic of automobiles and other vehicles.

Our invention aims to provide a simple, durable and inexpensive signal exhibitor which is particularly characterized by a novel coinpartment member affording a plurality of separate reflectors or compartments for incandescent lamps, and a transparent or translucent plate closing the compartments of said compartment member which permits the incandescent lamps to illuminate signs carried by the transparent plate. By using a suitable switch in connection with the exhibitor the incandescent lamps may be controlled for the display of different signs, and we employ novel means for supporting the incandescent lamps and the compartment member relative to an exhibitor casing.

The construction entering into our invention will be hereinafter described and then claimed, and reference will now be had to the drawing, wherein

Figure 1 is a front elevation of the signal exhibitor;

Fig. 2 is a longitudinal sectional view of the same;

Fig. 3 is a horizontal sectional view of the signal exhibitor;

Fig. 4 is a perspective view of a compartment member, and

Fig. 5 is a horizontal sectional view of another form of compartment member.

The signal exhibitor comprises a cylindrical casing having a rear wall 2 and a front open end through which access is had to the interior of the casing. The cylinder wall of the casing has its front edges flared, as at 3, and clamped on the flared edge of the casing is a channel retaining member 4 in the form of a split ring which has its ends provided with apertured lugs 5 adapted to be connected by a screw bolt 6 and nut 7 or other fastening means permitting of the retaining member being contracted about the flared edges 3 of the exhibitor casing 1. The channel shape of the retaining member 4 permits of said member holding a transparent or translucent sign plate 8 and this plate may be painted, stenciled or otherwise treated to afford a plurality of signs in superposed re-

lation, as shown in Fig. 1. For instance, the signs may be "Left," "Right," "Stop" and the characters of such words may be cut from an opaque piece of material 9 placed against the inner wall of the sign plate 8.

Mounted between the peripheral edges of the sign plate 8 and the flared edges 3 of the casing 1 are the edges of a compartment member 10, which is in the form of a metallic disk having a plurality of transversely disposed parallel pressed out portions affording oblong compartments 12, and as shown in Fig. 2 these compartments may be three in number to correspond to the number of signs shown in Fig. 1, while in Fig. 4 the compartment member 10 has been shown as having four compartments. The compartments vary in length due to the circular shape of the compartment members and each compartment has converging walls 12 extending inwardly from the base of the compartment member to a rear wall 13 of each compartment, and these converging walls are finished so as to provide deflectors by which rays of light may be reflected towards the sign plate 8.

As shown in Fig. 2 the compartment member may have transverse grooves or indentations 30 between compartments thereof and cushion members 31 may be mounted in the grooves to cushion the transparent plate 8.

Connected to the rear face of the compartment member 10, by screws 14 and nuts 15 or other fastening means are the ends of a channel shaped bracket or strap 16 to which are secured a plurality of socket members 17 adapted for detachably holding incandescent lamp sockets 18 having lamps 19. The lamp sockets 18 have leading-out wires 20 that extend through an insulator 21 carried by the cylindrical wall casing 1, and said leading out wires are adapted to extend to a suitable source of electrical energy and to one or more switches (not shown). The socket holders 17 are attached to the bracket 16 by screws 22 and nuts 23 or other fastening means, and the rear wall 13 has a large opening 25, permitting of the lamp socket being inserted and detachably mounted in the holder 17.

As indicating a suitable support for the signal exhibitor casing, we show a bracket 26 and detachably connected to said bracket are the apertured lugs 27 of the exhibitor casing, said lugs being carried by a plate 28 suitably connected to a wall of the casing.

As shown in Fig. 5, a compartment mem-

ber 32 may have walls converging to a lamp opening 33, thus eliminating the rear wall 13 as shown in Fig. 3.

We attach considerable importance to the fact that the compartment member is stamped and shaped from a single piece of material, and that said member may be made with as many compartments as are necessary in order that the signs of the exhibitor may be independently illuminated by incandescent lamps within the compartments of the member.

One embodiment of our invention has been illustrated, but it is to be understood that the structural elements are susceptible to such variations and modifications as fall within the scope of the appended claim.

What we claim is:—

As a new article of manufacture, a disk shaped compartment member for a signal exhibitor, said compartment member being made of a single piece of material forming a front wall pressed to provide a plurality of

rearwardly extending parallel transversely disposed compartments and transverse cushion holding grooves between said compartments, said compartments having substantially flat top and bottom walls and converging end walls, said compartments being three in number with two of said compartments equal in length and of less length than the remaining compartment, said remaining compartment being disposed between the first mentioned compartments, and all of said compartments having the walls thereof finished to afford reflectors; in combination with a translucent sign plate with characters depicted thereon, and means for supporting said plate adjacent said compartment member in such a manner as to bring said characters opposite said compartments.

In testimony whereof we affix our signatures.

JOSEPH A. SHEPHERD.
WILLIAM L. JOHNSTON.
